United States Patent Office

Des. 206,374
Patented Dec. 6, 1966

206,374

WINDOW SCREEN OR SIMILAR ARTICLE

Stanley D. Barnett, Mount Vernon, N.Y.
(490 Neperhan Ave., Yonkers, N.Y. 10701)

Filed Feb. 25, 1966, Ser. No. 1,175

Term of patent 14 years

(Cl. D13—1)

Fig.3

Fig.2

Fig.1

Fig.4

FIGURE 1 is a front elevational view of a window screen or similar article showing my new design;

FIGURE 2 is a rear elevational view thereof;

FIGURE 3 is a side elevational view thereof, as might be seen from the right hand portion of FIGURE 1; and

FIGURE 4 is a bottom plan view thereof, the top plan being similar.

I claim:

The ornamental design for a window screen or similar article, substantially as shown and described.
